Patented Sept. 16, 1913.

UNITED STATES PATENT OFFICE.

FRANK A. RAABE, OF STANTON, NEBRASKA.

FABRIC HOLDER AND EXHIBITOR.

1,073,519.

Specification of Letters Patent. Patented Sept. 16, 1913.

Application filed April 8, 1913. Serial No. 759,635.

To all whom it may concern:

Be it known that I, FRANK A. RAABE, a citizen of the United States, and a resident of Stanton, in the county of Stanton and State of Nebraska, have made certain new and useful Improvements in Fabric Holders and Exhibitors, of which the following is a specification.

My invention is an improvement in fabric holders and exhibitors and has for its object to provide a device of the character specified, especially adapted for holding a plurality of rolls of fabric, as for instance silks, cloths, rugs, oilcloths or linoleum, and for retaining the said fabrics in rolled condition or for permitting the said fabrics to be displayed, without the necessity of moving the rolls from place to place, and wherein the rolling and unrolling is done mechanically.

In the drawings: Figure 1 is a front view of the improved device; Fig. 2 is a section on the line 2—2 of Fig. 1; Fig. 3 is a partial side view; Fig. 4 is a section on the line 4—4 of Fig. 2; Fig. 5 is an enlarged longitudinal section of one of the rollers and its connections; Fig. 6 is a section on the line 6—6 of Fig. 5, and, Fig. 7 is a perspective view of one of the stop blocks.

The present embodiment of the invention comprises a substantially rectangular frame, consisting of a base 1, side bars 2 and 3 respectively connected with the base near the ends thereof, and a cross bar 4 connecting the upper ends of the side bars. The base 1 is of sufficient width to furnish a firm support, and the side bars 2 and 3 of the frame extend from the rear of the base, and the base extends beyond the said bars at each end, as indicated in Figs. 1 and 2. The side bar 2 is provided on its inner face, with a vertical series of hangers, each hanger being of resilient material and comprising a plate having one of its ends 4 secured to the side bar 2 by means of screws 5 or the like, and an inwardly offset portion 6 which carries a journal pin 7, the said journal pin having a head 8 secured to the portion 6 of the hanger in any suitable manner.

A block 9 in the form of a substantially rectangular frame is mounted for sliding movement on the inner face of the side bar 2 adjacent to each hanger, and each of the said blocks is provided at its base with a longitudinally extending slot 10, and the slot is engaged by screws 11, the said screws passing through the slot and being threaded

into the side bar 2, to slidably connect the block with the side bar.

A series of rollers 12 is provided, each of the said rollers having at one end an opening 13 for receiving the journal pin 7 of a hanger, and at its opposite end each of the said rollers 12 is engaged by an annular lateral flange 14 on a ratchet wheel 15, each of the said ratchet wheels having an axial journal pin 16 extending in the opposite direction to the flange. Each ratchet wheel is also provided with a transverse key or lug 17 on its inner face, the said lug extending diametrically of the flange, and each of the said keys or lugs is seated in the material of the roller 12, to prevent rotation of the ratchet wheel with respect to the roller. The side bar 3 is provided with an opening for each journal pin 16 in alinement with a journal pin 7 on the other bar 2, and the said journal pins 16 extend through the openings and beyond the outer face of the side bar 3.

A pawl 18 is pivoted to the side bar 3 adjacent to each ratchet wheel, by means of a screw 19 or the like, and each pawl is arranged to prevent movement of the roller in one direction. Each of the journal pins 16 has its outer end of polygonal shape as indicated at 20, to receive a crank 21, to rotate the roller, and each of the said pins is provided with an annular groove 22 at the outer face of the side bar 3.

A plate 23 is engaged with the groove of each journal pin, each of the said plates being of approximately semi-circular shape, as shown more particularly in Fig. 3, and a screw 24 is provided for holding each plate to the side bar, the said screw passing through an opening in the plate. The plates 23 prevent longitudinal movement of the roller, while at the same time not interfering with the angular movement of the said roller. It will be noticed from an inspection of Fig. 5, that the groove 22 of the journal pin is of greater width than the thickness of the plate, in order to lessen friction between the plate and the journal pin. Each roller 12 is preferably provided with a casting or facing in the shape of a tube 25 of paper, pasteboard, or the like, each of the said tubes 25 being of a cross section to fit the roller, and to permit the removal and replacement of the tubes. Each of the said tubes may be held in place by means of a

split ring 26, the said ring embracing the

tube and the roller at the end of the tube adjacent to the ratchet wheel, and the ends of the ring are flanged laterally, as shown at 27, and are engaged by a bolt and nut 28 to clamp the split ring on the tube.

5 A smoothing roller 29 is arranged on the base, the said roller resting in a groove 30 extending longitudinally of the base on the upper face thereof, and just in front of the 10 side bars 2 and 3, the said groove being a sufficient length to receive the roller. The roller is of such length that the ends thereof are approximately flush with the outer faces of the side bars, and the said roller is held 15 in place by means of bracket arms 31, each of the said arms being arched to fit the peripheral surface of the roller, and the said arms are secured to the base at the ends of the groove by means of a screw 32 or the 20 like.

That portion of the base in front of the groove between the side bars 2 and 3 is cut away to the level of the groove, as indicated at 33, and the base is provided with a longitudinally extending slot 34 at the end adjacent to the side bar 3 in the said cut away portion. A guide consisting of a plate composed of a portion 35 resting on the upper face of the cut away portion and a portion 36 offset upwardly from the said face is connected to the slot for adjustment longitudinally of the base, and by means of a bolt 37 passing upwardly through the slot and the portion 35 of the plate, and engaged by a wing nut 38 above the said portion 35. The head of the bolt 37 is received in a countersink or recess 39 in the under face of the base at the slot, to permit free movement of the bolt without interference 40 with the surface upon which the device rests.

The rollers are adapted to receive fabric material of any character, the said material being rolled on the rollers by means of the crank 21. When it is desired to place material on a roller, the crank is engaged with the portion 20 of the journal pin of the said roller, and the roller is rotated in a direction to wind up the cloth. The pawls prevent reverse movement of the rollers.

50 The cloth is wound on the tube 25, and when it is desired to exhibit the cloth from any particular roll, the free edge of the cloth is grasped and pulled outwardly, after the pawl adjacent to the roller has been lifted, to permit reverse movement of the roller. The rollers may be removed, by sliding the block 9 rearwardly, as indicated in dotted lines in Fig. 6, to move the said block out of position to be engaged by the portion 6 of the adjacent hanger. After the block has been so moved, the portion 6 of the hanger that carries the journal pin may be pressed toward the adjacent side bar 2, to release the roller from the flange of the ratchet 65 wheel, and the ratchet wheel may be then

moved laterally away from the said bar 3 to the journal pin 7 from the recess 13 of the roller. The screw 24 of the plate 23 adjacent to the said roller has meanwhile been loosened, to permit the plate to be turned out of engagement with the groove 22. The roller is now moved longitudinally toward the side bar 2, and also swung laterally to permit the journal pin 16 to be withdrawn from the opening of the side bar 2.

70 During the winding of the fabric on the rollers, the guide 35-36 is adjusted so that the edge of the cloth will engage the web connecting the two portions 35-36 of the guide, and the end of the said cloth is first 80 passed beneath the smoothing roller 29, before the said end is engaged with the roller. As the cloth winds on the roller 12, the smoothing roller holds the cloth to the base of the cut away portion, to cause the cloth 85 to wind smoothly and uniformly on the said roller 12, and the guide prevents lateral movement of the fabric, causing the same to wind in such manner so that the end of the roll of cloth is even and uniform.

90 The roller 29 is of sufficient weight to insure the smooth rolling of the fabric. The clamp ring 26 prevents angular movement of the tube 25 with respect to the roller and the said tube prevents injury to the cloth 95 from the roller 12. The said tube also furnishes a support for the roll of cloth in case it should be desired to remove the said roll as a roll from the roller. The smoothing roller 29 may be removed from its groove, 100 by loosening the screws 32 enough to permit the brackets 31 to be swung outwardly from above the ends of the roller. The cut away portion 33 is of approximately the same length as that portion of a roller 12 between 105 the free edge of the flange 14 and the opposite end of the roller. That is, the said cut away portion is of a length corresponding to the width of the widest strip of fabric that may be wound upon the rollers 12.

110 I claim:

1. A device of the character specified, comprising an open supporting frame, a series of vertically spaced hangers secured to the frame at one side thereof, each hanger 115 having a journal pin offset inwardly toward the opposite side of the frame, a roller for each hanger, each roller having an opening for the journal pin in one end, means at the opposite side of the frame for supporting the opposite end of each roller, and means in connection with the said supporting means for preventing reverse movement of the roller.

120 2. In a device of the character specified, 125 comprising an open supporting frame and rollers journaled in the frame, each roller having at one end an axial opening, a resilient hanger secured at one end to the supporting frame adjacent to each roller and 130

having at the other end a journal pin for
engaging the axial opening of the adjacent
roller, said end of the hanger being offset
toward the roller, and a block slideable on
5 the frame at the said end of each hanger
to prevent withdrawal of the journal pin,
each roller having means for engaging the

opposite side of the frame to support the
roller.

FRANK A. RAABE.
